UNITED STATES PATENT OFFICE.

WILLIAM S. HAMM, OF CHICAGO, ILLINOIS, ASSIGNOR TO THE ADAMS & WESTLAKE COMPANY, A CORPORATION OF ILLINOIS.

LAMP.

SPECIFICATION forming part of Letters Patent No. 690,275, dated December 31, 1901.

Application filed April 20, 1901. Serial No. 56,750. (No model.)

To all whom it may concern:

Be it known that I, WILLIAM S. HAMM, a citizen of the United States, and a resident of Chicago, county of Cook, and State of Illinois, have invented certain new and useful Improvements in Lamps, of which the following is a specification, and which are illustrated in the accompanying drawings, forming a part thereof.

10 My invention relates to improvements in lamps, and is particularly adapted for use in burning acetylene gas, which requires a thorough ventilation of the lamp in order that the gas led to the burners may not become heated before being consumed, although, as will be obvious, it may be employed for burning ordinary illuminating-gas.

The lamp is of the type known as "wall" or "panel" lamps, being designed to be placed 20 along the paneling or side of railway-cars, for which purpose the present invention has especial reference, or against the wall of a chamber or other room.

The objects of the invention are generally 25 to provide an ornamental and attractive lamp which shall be simple in construction and compact in form, so as to utilize as little space as possible, and one which may be successfully used for burning acetylene gas.

30 The invention consists, in general terms, in a body comprising a concave reflector and a glass front, the two forming a flame-chamber and being spaced apart at their edges to provide ample ventilation.

35 It consists, further, in various details of construction relating to the lamp-body and its means of support, as hereinafter disclosed.

The embodiment of the invention is illustrated in the accompanying drawings, in 40 which—

Figure 1 is a vertical section of the lamp. Fig. 2 is a side and Fig. 3 a front elevation, respectively, of the lamp. Figs. 4 and 5 are details of construction, the former showing 45 the hinge for the front or lens part of the lamp and the latter the latch or catch for securing the lens when closed.

The essential parts of the lamp consist of a concave reflector 10 and a glass front 11, 50 preferably of the same contour as the reflector, providing between them a flame-cham-

ber, into which the service-pipe 13, having a burner 14, is led through an aperture 15 near the lower edge of the reflector.

Formed at the edge of the reflector 10 is an 55 outwardly-flaring curved flange 16, which projects, preferably, to the plane of the frame of the glass front 11 and is designed to deflect from the woodwork or wall at the back of or in the vicinity of the lamp the heated 60 air and products of combustion escaping from the flame-chamber through the space between the edges of the reflector and the glass front. While with view to symmetry the flange 16 is continued entirely around the lamp, the 65 upper portion only is depended upon for the performance of the function mentioned.

The reflector 10 and the front 11 are suitably spaced at their edges, as illustrated in Fig. 1, to insure a proper ventilation all 70 around the lamp, thus providing for the ready entrance of air at the bottom and sides and the equally ready escape of the heated air and products of combustion at the top.

The front 11 is carried by a frame consisting of a band 17, having its inner edge offset, as at 18, to form a seat for the glass, the outer member 19 of the frame being riveted or otherwise suitably secured to the band 17, and an insulating-band 20 is interposed between the member 19 and the edge of the glass.

In order to avoid the interference of drafts of air with the flame, a band 21 is interposed in the ventilating-space between the reflector and the edge of the front and is held in position by brackets 22, secured to the flaring flange 16, which in addition to supporting the band 21 also provides means for spacing the reflector and the front, the frame of 90 the latter when closed resting against their free ends. The band 21 is V-shaped in cross-section, the apex of the V being pointed into the flame-chamber. By this arrangement and construction the band 21 not only serves to 95 prevent the emission of light through the ventilating-space, but it also breaks up the air-currents entering at the sides and bottom of the lamp, so that the flame will not be disturbed by drafts. It is aided in attaining 100 this result by its peculiar formation—that is to say, because of its channeled form it is

more effective in breaking up the air-currents entering from the outside than would be a flat ring, and, on the other hand, its diverging walls offer little resistance to the escaping heated air and products of combustion, so that a constant and thorough circulation is always kept up.

The lamp is attached to the wall or panel of the car or room by a ring 23 of sufficient width to properly space the back of the lamp or reflector 10 from the wall or panel and provide an air-space to prevent the scorching of the woodwork.

Attached to the outer edge of the ring 23 are two or more brackets 24, which receive the outwardly-extending flange 16 of the reflector 10, a layer 25 of heat-non-conducting material, such as asbestos, being interposed between the flange 16 and the brackets and the three parts being secured together by screws 26, which also enter and secure the brackets 22, supporting the deflecting-band 21. If desired, the brackets 24 may form lugs of a ring of the same configuration as the flange 16, as shown. The ring 23 may have a series of apertures closed by jewels 27, and for the purpose of ornamentation and for adding to the attractiveness of the lamp provision is made for illuminating these jewels, as by cutting in the reflector 10 near its edge a series of openings 28. By means of the brackets 24 the reflector 10 is spaced from the ring 23, whereby ample ventilation is provided to carry off the heat conducted through the reflector.

The front glass frame is hinged at 29 at the side to an arm 37, projecting from one of the brackets 24, and at the opposite side is provided with a spring-catch 30, which engages, when the front is closed, one wall of the band 21. A finger 31 passes through an aperture in the bracket 24 at that side of the lamp and is provided with a head 33 and a flange 34 to prevent it from being withdrawn or falling out of the bracket. The inner end of this finger is beveled, as shown at 32, and an thrust of the finger against the spring-catch 30 disengages the latter from the band 21. The gas is controlled by a key 35, projecting 50 through an aperture 36 in the ring 23.

While I have described and illustrated my lamp as elliptical in shape, its general form is immaterial and may be varied as desired.

I claim as my invention—

55 1. In a lamp, in combination, a concave reflector, and a glass front covering the face of the reflector and forming therewith a flame-chamber, the reflector and front being spaced apart to provide a passage constituting the air-induction port and smoke-flue of the lamp.

2. In a gas-lamp, in combination, a reflector, a glass front spaced at its edge therefrom, and providing a passage therewith constituting the air-induction port and smoke-flue of 65 the lamp; and a deflecting-flange integral with the reflector and extending over the glass front at the top of the lamp, the edge of

the reflector overhanging such passage at the top.

3. In a gas-lamp, in combination, a reflector, a glass front spaced at its edge therefrom and forming with the reflector a flame-chamber, and providing a passage between the edge of the reflector and the glass front constituting the air-induction port and smoke-flue of the lamp, and an outwardly-flaring curved flange formed on the reflector and projecting over the space between the reflector and the edge of the front, the edge of the reflector overhanging such passage at the top. 70 75 80

4. In a gas-lamp, in combination, a reflector, a glass front spaced therefrom and forming with the reflector a flame-chamber, and a deflecting-band supported in the space between the front and the reflector. 85

5. In a gas-lamp, in combination, a reflector, a glass front spaced therefrom and forming with the reflector a flame-chamber, and a band supported in the space between the front and the reflector, and having its outer face 90 channeled.

6. In a gas-lamp, in combination, a reflector, a glass front spaced at its edge therefrom and forming with the reflector a flame-chamber, and a band supported in the space between the edge of the front and the reflector, the band being V-shaped in cross-section and the walls thereof diverging from the flame-chamber. 95

7. In a gas-lamp, in combination, a concave reflector, a glass front spaced therefrom and forming with the reflector a flame-chamber, a flange projecting over the space between the reflector and the front, and a deflecting-band supported in the space between 100 the reflector and the front.

8. In a gas-lamp, in combination, a concave reflector, a glass front spaced from and hinged thereto and forming with the reflector a flame-chamber, and brackets for spacing the front and the reflector, the front when closed being seated against the spacing-brackets. 110

9. In a gas-lamp, in combination, a concave reflector, a glass front forming with the reflector a flame-chamber, a ring, and means for securing the reflector to and spacing it from the ring, the said ring being located at the rear of the reflector and interposed between the latter and the wall or other support to which the lamp may be secured. 115 120

10. In a gas-lamp, in combination, a concave reflector, a glass front forming with the reflector a flame-chamber, an apertured ring, means for securing the reflector to the ring, the said ring being located at the rear of the reflector and spacing the same from the wall or other support to which the lamp may be secured, and apertures through the reflector for admitting light from the flame-chamber to the interior of the ring. 125 130

11. In a gas-lamp, in combination, a concave reflector, a hinged glass front spaced at its edge from and forming with the reflector a flame-chamber, a flange projecting from the

reflector and over the space between the reflector and the front, brackets secured to the flange and against which the front is seated when closed, and a band supported by the brackets in the space between the reflector and the front.

12. In a gas-lamp, in combination, a concave reflector, a hinged glass front spaced at its edge from and forming with the reflector a flame-chamber, a band supported in the space between the edge of the front and the reflector, and a spring-catch carried by the front and engaging the band.

13. In a gas-lamp, in combination, a concave reflector, a hinged glass front spaced from and forming with the reflector a flame-chamber, a curved flange projecting from the edge of the reflector and over the space be-

tween the reflector and the edge of the front, a deflecting-band supported in the space between the front and the reflector, a catch carried by the front for engaging the deflecting-band, and a pin for disengaging the catch from the deflecting-band.

14. In a gas-lamp, in combination, a reflector, a glass front covering the face of the reflector and forming therewith a flame-chamber, a vent for the products of combustion at the top of the flame-chamber, and a hood projecting forwardly over the flame-chamber 30 vent for deflecting the vapors away from the wall.
